UNITED STATES PATENT OFFICE.

CHARLES E. BENTLEY, OF NEW YORK, N. Y.

DESIGN FOR A BOTTLE.

SPECIFICATION forming part of Design No. 20,032, dated July 15, 1890.

Application filed June 3, 1890. Serial No. 354,143. Term of patent 7 years.

To all whom it may concern:

Be it known that I, CHARLES E. BENTLEY, a citizen of the United States, residing at the city of New York, in the county and State of New York, have invented and produced a new and original Design for a Bottle, of which the following is a specification, reference being had to the accompanying drawings, forming part thereof.

10 Figure 1 is a side view of a bottle showing my design, and Fig. 2 is an edge view thereof, these two views being deemed necessary to fully illustrate the design.

15 The leading features of my design for a bottle or dressing-case ornament consist in the configuration of its body portion, which in side view, Fig. 1, presents a broad fan-shaped outline having two opposite concave and comparatively sharp side edges, which merge upward into a neck or stem, and a lengthwise convexed or rounded base or bottom, into which the sides merge. In edge view, Fig. 2, the design presents to the eye a comparatively narrow or thin outline, formed of sides which 20 gradually diverge downward from the neck or stem to the convexed elliptical base or bottom.

25 In the drawings, A represents the body of

the bottle or ornament, which has an upper neck or stem a , which may be of like diameter throughout, but is shown slightly enlarged toward the top. The opposite sides 1 1 of the bottle are convexed laterally and merge into comparatively sharp side marginal edges 2 2, which, however, merge at the top into the rounded neck or stem, and are concaved vertically from the neck to the ends of the upwardly-convexed base or bottom 3, which the sides also meet. The base or bottom is broadest at the center and gradually tapers to its rather sharp ends 4 4, which meet the sharp 30 side marginal edges 2 2 of the body; hence if viewed from the bottom the bottle or ornament presents an elliptical outline convexed lengthwise between its ends.

35 A cut-glass stopper is shown in the neck of the bottle.

I claim as my invention—

40 The design for a bottle, substantially as herein shown and described.

CHARLES E. BENTLEY.
